(57) **CLAIM**

We claim the ornamental design for a parking meter mechanism, as shown and described.

DESCRIPTION

FIG. 1 is a front perspective view from above of a parking meter mechanism showing our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a second perspective view from above thereof; and, FIG. 9 is a perspective view from below thereof.

The ornamental design which is claimed is shown in solid lines in the drawings. The broken lines in the drawings are for illustrative purposes only and form no part of the claimed design.
